Primary Examiner — Marcus A Jackson*(74) Attorney, Agent, or Firm* — Quickpatents, LLC;
Kevin Prince(57) **CLAIM**

The ornamental design for a vehicle rear lamp, as shown and described.

DESCRIPTION

FIG. 1 is a top, right, front perspective view of a vehicle rear lamp, showing my new design;

FIG. 2 is a bottom, right, front perspective view thereof;

FIG. 3 is a front elevational view thereof;

FIG. 4 is a right-side elevational view thereof;

FIG. 5 is a rear elevational view thereof;

FIG. 6 is a top plan view thereof;

FIG. 7 is a left-side elevational view thereof;

FIG. 8 is a bottom plan view thereof;

FIG. 9 is a bottom, rear perspective view thereof;

FIG. 10 is a top, rear perspective view thereof; and,

FIG. 11 is a left, rear perspective view thereof.

The broken lines in the figures depict portions of the vehicle rear lamp that form no part of the claimed design.
